Des 2489

Assign to

The Union Steam Mill Company of same place

Letters Patent No. 2489, Dated Oct. 9, 1866

Design for a Trade Mark.

The Schedule referred to in the Letters Patent and making part of the same.

To whom it may concern

Be it known that I, William Freedman of St. Louis and State of Missouri, have invented or produced a new and original Design for a Trade Mark; and I hereby declare the following to be a full, clear, and exact description of the same, reference being had to the accompanying drawing.

The Design consists of three Dominos arranged as shown in the drawing. The outer dominos are placed so as to be tangent to the length of the central one, their interior and opposite edges being brought in contact with the respective ends of the central domino, so as to give a T-shape to each end of the device. The number of spots on the dominos amounts to thirty, the highest number made in the game of dominoes, called "Muggins," and is intended to be typical of the quality of the labor in the barrel or case to which the brand is applied. Above the design may be inscribed the words "Compte grec. Courte." 196, and below it can be placed the name of the firm or company by which the brand is possessed and used, and the whole "Domino Brand" thus arranged may be enclosed or surrounded by a suitable frame or border.

Having described my invention, what I claim and desire to secure by Letters Patent is;

The Design for a Trade Mark as herein shown and described. An witness whereof, I have signed my name to this Specification before two subscribing witness
